UNITED STATES PATENT OFFICE.

WILLY QUINT, OF WILMERSDORF, NEAR BERLIN, GERMANY.

PACKING FOR TUBES OF SURFACE CONDENSERS.

937,547.

Specification of Letters Patent. Patented Oct. 19, 1909.

Application filed May 22, 1908. Serial No. 434,318.

To all whom it may concern:

Be it known that I, WILLY QUINT, a subject of the King of Prussia, German Emperor, and residing at Wilmersdorf, near Berlin, in the Kingdom of Prussia, German Empire, have invented certain new and useful Improvements in India-Rubber Packings for the Tubes of Surface Condensers and Similar Tubular Apparatus, of which the following is a specification.

The employment of india-rubber as a packing-means for the tubes of surface-condensers and similar tubular apparatus is known, as is also the coaction of the excess of the atmospheric pressure with respect to the vacuum in the condenser. Up to now, two forms of this packing have been known. There is first an older form, in which the cast-iron frontal walls of the condenser have annular projections surrounding the holes through which the ends of the condenser-tubes extend beyond said annular projections. Coöperating with each annular projection and the respective tube-end is a piece of india-rubber hose drawn over the said parts and forming the packing so as to prevent the entrance of atmospheric air into the condenser at the junction of the tube-walls and tubes. There are thus in this form of construction two pieces of india-rubber hose for each tube, one at each end, and every piece may be replaced by a fresh one, which is an advantage of this form of construction. But this advantage is offset by the disadvantage that the tube-walls with their numerous annular projections are difficult of manufacture, and further-more said projections entail comparatively large spaces between the tubes inside the condenser. These two disadvantages are not to be found in the second of the two known forms of construction, because with this the tube-walls remain perfectly flat or plane; and the tube-ends projecting above the outer surface of this wall are packed by means of an india-rubber plate common to them all and having perforations for the tubes. But in fact there is also disadvantage likely to offset the advantage to be found in the substitution of a common packing-plate for a large number of separate packings because in the case of the packing-plate becoming loose at one tube, the whole india-rubber plate must be replaced by a fresh one although it is perfectly sound at all the other tubes of the respective group.

There are thus advantages and disadvantages in either form of construction, and it is the object of my invention to combine the advantage of the two forms, and avoid at the same time the disadvantages of the same.

My invention is illustrated in the accompanying drawings, in which—

Figure 1 shows a portion of a tube wall of a tubular apparatus, and two pieces of tubes, one in longitudinal section, the other in elevation, the whole being furnished with my improved packing; and Fig. 2 is a similar view, showing a somewhat modified form of construction.

The principle embodied in these two forms of my improved packing is the same. In either case the tube walls are provided with separate annular projections which project over the surface or plane of the tube-wall in exactly the same manner as did the cast-iron annular projections that were cast in one piece with the tube-wall, the difference being only that in my invention the annular-projections are not cast in one piece with the wall. But, still, they may hang together, i. e. be formed of one piece of material, particularly sheet-metal. This construction is shown in Fig. 1, in which *a* is a portion of a tube-wall of a tubular apparatus, for instance of a surface-condenser. This tube-wall is perfectly flat, that is to say, it has no annular projections cast in one piece with the wall. But there are annular projections *b*² formed out of a sheet-metal plate *b* arranged in front, or at the outside, of the wall *a*. These projections form substitutes for those cast in one piece with the wall, the casting of which is very difficult, which difficulty is thus avoided, and the spaces occupied formerly by the cast projections are saved and can usefully be employed for increasing the number of tubes in a given area of surface. The tubes *c* project over the projections *b*², and pieces *d*² of india-rubber hose take over the ends *c*' of the tubes *c*, as well as over the projections *b*', just as they did in the old form. But in my improved construction the single or separate packings, of india-rubber hose, instead of a perforated india-rubber plate, are used in connection with a flat or plane tube-wall, such as *a*. All this is true also with respect to the somewhat modified form of construction shown in Fig. 2. The only difference with respect to Fig. 1 is, that the annular projections *b*² are not united with each other

but are formed by separate pieces of tube b' , each of which is fixed in a hole of the tube-wall, the holes being so much wider, or larger in diameter, that the tubes c can be 5 of the same size as in the case first-described. There is in this second case the advantage with respect to the first, that the india-rubber pieces d which take around the tube-ends c' with the same tension as in the first 10 case, take around the projections b^2 with a comparatively stronger tension because of the larger circumference of the ends of the pieces of tube b .

Having now described my invention what 15 I desire to secure by a patent of the United States is:

1. In a tubular apparatus having pieces of india-rubber hose taking over the projecting ends of the tubes and forming packings for 20 the same, the combination, with said tubes and packings, of completely flat tube-walls, and annular projections formed separately with respect to said tube-walls and arranged so as to correspond in position to the tube- 25 holes of said walls; said pieces of hose taking also over said annular projections, for the purpose as described.

2. In a tubular apparatus having tube-walls, tubes projecting over said walls, and 30 pieces of india-rubber hose taking over the

projecting ends of said tubes and forming packings for the same at said walls; the combination with said tubes and packings, of completely flat tube-walls, and annular projections formed separately with respect to 35 said tube-walls and forming substitutes for integrally formed projections and arranged so as to correspond in position to the tube-holes of said walls, for the purpose as described. 40

3. In a tubular apparatus having completely flat tube-walls, tubes projecting over said walls, and pieces of india-rubber hose taking over the projecting ends of said tubes and forming packings for the same at said 45 walls; the combination with said tubes and packings, of annular projections formed separately with respect to said tube walls and being integrally connected with each other, said annular projections forming substitutes for projections formed integrally with the tube-wall, the latter being left flat, for the purpose as described. 50

In witness whereof I have hereunto set my hand in presence of two witnesses.

WILLY QUINT.
